UNITED STATES PATENT OFFICE.

GEORGE W. BURKE, JR., OF DAYTON, OHIO.

CRASHPROOF FIRE WALL.

Application filed September 12, 1922. Serial No. 587,832.

To all whom it may concern:

Be it known that I, GEORGE W. BURKE, Jr., a citizen of the United States, residing at Dayton, in the county of Montgomery and State of Ohio, have invented certain new and useful Improvements in Crashproof Fire Walls, of which the following is a specification.

This invention relates to fire prevention means for air craft and more particularly to a fire proof bulkhead to be placed between the engine and the gas tank of an airplane.

Flying by plane is necessarily fraught with numerous dangers and the most hazardous of all is fire. In most cases where planes have caught fire it has been due to bursting of the gas tank allowing the gas to spray on the hot engine or manifold or come in contact with a spark. Very often the gas tank bursts on the crash of the plane resulting in enormous loss of life and property which might have been saved had not the accident occurred to the tank.

It is therefore the prime object of my invention to provide means which will effectually prevent bursting of the gas tank on impact of the plane with the ground in a crash and further, to resiliently absorb the shock, gently and gradually cushioning the impact of the tank. It is a further object of my invention to so construct the gas tank cushioning means that it will also act as a fire proof bulkhead to minimize the danger of fire due to spraying of gasoline on the hot parts of the engine from a bursted tank.

Further objects will become apparent from the claims and from the description of the accompanying drawing, in which:

Figure 1 is a side elevation of my device with portions shown broken away;

Figure 2 is an enlarged detail view of one of my shock absorbing members.

In the drawing 2, 2' designate the longérons of the plane which carry and support the weight of the gas tank 4 and engine 6. Between the gas tank 4 and engine 6 is placed my bulkhead generally designated 8 which comprises an aluminum back plate 10 extending the full width and height of the fuselage structure, a front plate 12 of the same material constructed with reinforcing

ribs 14, and springs 16 of the hour-glass type arranged between the two bulkhead walls 10 and 12 to resiliently and gradually absorb the impact pressure of the gas tank 55 on the engine should the plane crash. The front plate 12 extends the full section width and height as does the plate 10 and both plates may be made of other material than aluminum provided it be fire proof and of sufficient strength and lightness.

The bulkhead 8 may be assembled as a unit and securely fastened between the engine and gas tank to the longérons or in any other suitable manner, or it may be assembled in place. An additional bulkhead may be arranged between the pilot's seat and the gas tank and the sides of the bulkheads may be coated or faced with asbestos.

What I claim and desire to secure by Letters Patent is:

1. In aircraft, a fire proof bulkhead of light material and adapted for resilient resistance to impact pressure, located between the fuel tank and engine. 75

2. In aircraft, a fire proof bulkhead comprising light fire proof material construction and arranged to provide a resilient shock absorbing means between the fuel tank and another section of said aircraft. 80

3. A fire proof bulkhead for aircraft located adjacent and in conjunction with fuel tank comprising fire proof walls and resilient means disposed in conjunction therewith for absorbing impact pressure of said tank. 85

4. A fire proof bulkhead for airplanes comprising, a plurality of spaced apart walls, said walls being of light fire proof material and resilient means disposed therebetween for absorbing impact shocks of one section 90 of the airplane against another part thereof.

5. In aircraft, a fire proof bulkhead between the fuel tank and another portion of the ship comprising a wall of light fire proof material next said fuel tank, a second wall of similar material disposed adjacent and in conjunction with said other section and means therebetween for resiliently and gradually absorbing impact pressure of said tank against said other section. 95

In testimony whereof I affix my signature.

GEORGE W. BURKE, JR.
